CLAIM

The ornamental design for an abdominal exerciser frame, as shown and described.

DESCRIPTION

FIG. 1 is a perspective view of an abdominal exerciser frame showing the new design;

FIG. 2 is another perspective view thereof;

FIG. 3 is a front elevation view thereof;

FIG. 4 is a back elevation view thereof;

FIG. 5 is a left-side view thereof;

FIG. 6 is a right-side view thereof;

FIG. 7 is a top plan view thereof;

FIG. 8 is a bottom plan view thereof;

FIG. 9 is a perspective view an abdominal exerciser comprised of multiple abdominal exerciser frame components; and,

FIG. 10 is an enlarged view of the encircled portion in FIG. 9.

The broken lines shown in FIGS. 1-4 and 7-10 are included for the purposes of showing portions of the article and environmental structure and forms no part of the claimed design. The dot-dash lines in FIG. 9-10 represent an enlarged view and forms no part of the claimed design.

1 Claim, 10 Drawing Sheets
